SELF AUDIO MONITOR FOR SPEECH THERAPY

Claude M. Baldwin, 3400 Whitesburg Drive,
Huntsville, Ala. 35802

Filed Jan. 26, 1972, Ser. No. 221,128

Term of patent 14 years

Int. Cl. D19—07
U.S. Cl. D26—1 R

The single figure is a perspective view of a self audio monitor for showing my new speech therapy design.

I claim:

The ornamental design for a self audio monitor for speech therapy, substantially as shown.
